(57) **CLAIM**

The ornamental design for a bumper hitch step, as shown and described.

DESCRIPTION

FIG. 1 is a perspective view of a bumper hitch step ready for use, on an unclaimed vehicle.

FIG. 2 is a top plan view of the bumper hitch step of FIG. 1.

FIG. 3 is a bottom plan view of the bumper hitch step of FIG. 1.

FIG. 4 is a front elevation view of the bumper hitch step of FIG. 1.

FIG. 5 is a rear elevation view of the bumper hitch step of FIG. 1.

FIG. 6 is a side elevation view of the bumper hitch step of FIG. 1; and,

FIG. 7 is an opposite side elevation view of the bumper hitch step of FIG. 1.

The broken lines shown in the drawings are included for the purpose of illustrating the operating environment of the bumper hitch step, that forms no part of the claimed design.

1 Claim, 7 Drawing Sheets
